(57) CLAIM

I claim the ornamental design for the razor, as shown and described.

DESCRIPTION

FIG. 1 is a top perspective taken from the left side of the razor of the present invention.

FIG. 2 is a top plan view of the razor of FIG. 1.

FIG. 3 is a left side view of the razor of the present invention, the right side view being the mirror image thereof.

FIG. 4 is a bottom plan view of the razor of the present invention attached.

FIG. 5 is a front elevational view of the razor of FIG. 1; and, FIG. 6 is a back elevational view of the razor of FIG. 1.
